ATTORNEY

UNITED STATES PATENT OFFICE.

CHARLES T. COE, OF NEW YORK, N. Y.

DESIGN FOR A GRATE.

SPECIFICATION forming part of Design No. 24,504, dated July 23, 1895.

Application filed May 28, 1895. Serial No. 551,005. Term of patent 7 years.

To all whom it may concern:

Be it known that I, CHARLES T. COE, a citizen of the United States of America, residing in New York, in the county and State of New York, have invented and produced a new and original Design for Furnace-Grates, of which the following is a specification, reference being had to the accompanying drawing.

My invention has reference to a new and original design for furnace-grates, the nature of which will be more fully understood when described in connection with the annexed drawing, showing a perspective view of a grate.

Referring to the drawing, the letters *a* *a* designate transverse ribs, from which project, at substantially right angles, several longitudinal parallel arms *b*. In said arms are formed lateral transverse depressions *c*, grad-

ually enlarging downwardly. These depressions alternate on opposite sides of the arms and the several openings on the same sides of the arms connect, forming shield or heart shaped portions *d*. From opposite sides of the grate extend stepped lugs or portions *e*. 25

The leading feature of my design consists in the arms *b* provided with alternating lateral recesses and the lugs *e* extending from opposite sides of the grate, as described and shown.

What I claim as new is— 30

The design for a grate, substantially as shown and described.

In testimony whereof I affix my signature in the presence of two witnesses.

CHARLES T. COE.

Witnesses:
